UNITED STATES PATENT OFFICE.

HENRY W. GANTNER, OF COLUMBUS, OHIO.

DESIGN FOR A COMBINATION ADVERTISING SIGN AND MAIL-BOX SUPPORT.

Application filed November 9, 1928. Serial No. 28,812. Term of patent 14 years.

To all whom it may concern:

Be it known that I, HENRY W. GANTNER, a citizen of the United States, residing at Columbus, in the county of Franklin and State of Ohio, have invented a new, original, and ornamental Design for Combination Advertising Sign and Mail-Box Support, of which the following is a specification, reference being had to the accompanying drawing, forming a part thereof.

I claim:

The ornamental design for a combination advertising sign and mail box support as shown.

HENRY W. GANTNER.
